UNITED STATES PATENT OFFICE

2,339,968

LUGGAGE BAG

Joseph Wein, Chicago, Ill.

Application December 18, 1942, Serial No. 469,409

3 Claims. (Cl. 190—41)

The invention relates generally to luggage bags.

One object of the invention is to provide a luggage bag of the type which is usually formed of flexible material, such as canvas, and one or more openings therein for access to the luggage space or spaces therein, with an improved dust-proof closure for the openings to protect the clothes in the bag.

Another object of the invention is to provide a closure for the openings between flexible members of a bag or a compartment thereof which is particularly applicable to luggage bags formed of flexible material and whereby the members will be securely connected together when the opening is closed.

Other objects of the invention will appear from the detailed description.

The invention consists in the several novel features which are hereinafter set forth and more particularly defined by claims at the conclusion hereof.

In the drawing:

Fig. 1 is a perspective of a luggage bag embodying the invention.

Fig. 2 is a transverse section on an enlarged scale of the parts forming the closure for the opening provided for access to one of the compartments in their closed position.

Fig. 3 is a similar view with the parts forming the closure spread apart.

Fig. 4 is a view of the closure with the parts partially spread apart to illustrate their construction.

The invention is exemplified as applied to a luggage bag of the duffel type which comprises a body or main section *a* adapted to contain suits and which is foldable across its center; pocket-sections *a*¹ and *a*² attached to one side of the main section; and a pocket-section *a*³ attached to the other side of and extending across the main section. A handle *b* is usually secured to fold across the main section. The bag and pockets have walls formed of canvas or other suitable flexible material. The main section *a* and the pocket-sections *a*¹, *a*² and *a*³ may each be provided with a closure embodying the invention. The same construction of closure is used for all sections, and therefore a description and illustration of one closure suffices for all.

The walls of each bag-section for which the improved closure is used comprise flexible members *10* and *11* which are separable along the portion of the section where an opening is desired for access to the luggage-space in said section. The marginal portion *10a* of member *10*

and the marginal portion *11a* of member *11* are adapted to overlap each other adjacent the corner of the section where the opening is desired. The edge of portion *10a* of member *10* is folded, 5 as at *12*, by a row of stitches *13*. From this fold *12* the canvas is extended to form an inturned flexible strip or flap *14* which is adapted to be folded so it will underlie the marginal portion *10a* of member *10*. A binding strip *15* is stitched around the inner edge of strip or flap *14*. The portion *11a* of member *11* is adapted to underlie the strip or flap *14* and the marginal portion *10a* of member *10*. Portion *11a* is shown as attached with a corner-strip *16* by a seam *16a* to member *11a* for convenience in fabrication, but is in effect a continuation of said member. Along its inner edge, portion *11a* is folded and secured by a seam *11b* and is extended outwardly from the seam to form a flexible strip or flap *17* which extends outwardly from the fold and is adapted to lap the portion *11a*. A binding strip *18* is stitched to the free outer edge of strip *17*. Members *10* and *11* and the flaps *14* and *17* are formed of flexible material, such as canvas, so that they may be flexed apart for the opening. The strip *14* on member *10* is adapted to be inserted or folded between the strip *17* and the portion *11a* of member *11*, and the strip or flap *17* is insertable and foldable between the strip or flap *14* and the portion *10a* of member *10* to produce an interfold 20 of approximately parallel portions between the members and strips for securely closing the opening against admission of dust. The flexibility of the strips or flaps and the members permits them to be so interfolded and separated.

Fastening means is provided to secure the strips *14* and *17* together and folded between each other, and thelapping portions of members *10* and *11*, or in said interfolded relation. This means may consist of a series of fasteners, each of which comprises a snap socket *20* secured in the strip *14* and a stud *21* secured in the strip *17*.

In using the closure the members *10* and *11* and strips or flaps *14* and *17* are flexed apart, 45 as illustrated in Figs. 3 and 4. When the opening is to be closed, the strip or flap *14* on member *10* is inserted or folded to lie between strip *17* and marginal portion *11a* of member *11* and strip or flap *17* is inserted or folded to lie between strip *14* and the marginal portion *10a* of member *10*. The studs *21* are then pressed into the sockets *20* and the strips and marginal portions will be secured to close the opening, as illustrated in Fig. 2. In order to additionally hold the portion *11a* of member *11* to underlie the strip *14* on

member 10, a snap fastener is used which comprises a socket 22 secured to the strip 14 adjacent its outer margin 11^a of strip 11 and a stud 23 which is secured to the marginal portion. In opening the closure, the stud and socket 22, 23 will first be disconnected and the member 10 and its strip or flap 14 with the strip or flap 17 between them can be flexed, as shown in Fig. 4. Next the series of stud fastners 20, 21 will be successively forced apart. A finger may then be inserted over marginal portion 11^a and between the inner edge of strip 14 and strip 17 for separating the studs 21 from the socket 20. The closure is applicable to any portion of the pockets or section of the bag, and usually extends along one corner, as at a⁴ and angularly as at a⁵ a sufficient distance to provide an opening of sufficient area for access to the articles in the pocket. It will be understood that any suitable fasteners may be used.

When the pockets or bag is closed, the flexible members and strips are effectively secured together to form a dust-proof closure for the protection of the contents of the bag. The invention is particularly applicable to luggage bags which are formed, or in which pockets are formed, of flexible material.

The invention is not to be understood as restricted to the details set forth, since these may be modified within the scope of the appended claims without departing from the spirit and scope of the invention.

Having thus described the invention, what I claim as new and desire to secure by Letters Patent is:

1. A closure for a luggage bag comprising a pair of members which are flexible for separation to provide an opening for access to the luggage in the bag or a portion thereof and are provided with edges adapted to meet along and form a substantially right angled corner, flexible strips on the edges of the members, respectively, and inwardly foldable into substantially parallel overlapping relation in the bag, a flexible strip attached to the inner edge of the infolded strip on one of the members and adapted to be interlaid between the other member and its infolded strip, and means for detachably securing together

inwardly of the corner the folded strip on one member and the interlaid strip on the other member, said securing members being concealed when the members are closed.

5 2. A closure for a luggage bag comprising a pair of members which are flexible for separation to provide an opening for access to the luggage in the bag or a portion thereof and are provided with edges adapted to meet along and form a substantially right angled corner, flexible strips on the edges of the member, respectively, and inwardly foldable into substantially parallel overlapping relation in the bag, a flexible strip attached to the inner edge of the infolded strip on one of the members and adapted to be interlaid between the other member and its infolded strip, means for detachably securing together inwardly of the corner the folded strip on one member and the interlaid strip on the other member, said securing members being concealed when the members are closed, and means outwardly of the securing means for the interlaid strip and inwardly of the corner for securing the infolded strips on the members together, said latter securing means being concealed when the bag is closed.

10 3. A closure for a luggage bag comprising a pair of members which are flexible for separation to provide an opening for access to the luggage in the bag or a portion thereof and are provided with edges adapted to meet along and form a corner, flexible strips on the edges of the members, respectively, and inwardly foldable into substantially parallel overlapping relation in the bag, a flexible strip attached to the inner edge of the infolded strip on one of the members and adapted to be interlaid between the other member and its infolded strip, and means for detachably securing together inwardly of the corner the folded strip on one member and the interlaid strip on the other member, said securing members being concealed when the members are closed, and a snap-fastener outwardly of the securing means for the interlaid strip and inwardly of the corner for securing the infolded strip on the members together, said latter means being concealed by the members along their corners.

JOSEPH WEIN.
